UNITED STATES PATENT OFFICE.

JAMES POLLOCK, OF NEW YORK, N. Y.

FURNACE FOR BURNING FINE FUEL.

Application filed July 13, 1925. Serial No. 43,183.

This invention relates to improvements in furnaces for burning fine fuel in suspension. In my Patent No. 1,530,321, dated March 17, 1925, I have shown a furnace in which the fuel is blown upwardly through a nozzle into a furnace chamber which is circular in cross section and which gradually enlarges in diameter from the bottom upwardly, and in which I have provided means for blowing air upwardly into the chamber adjacent the nozzle to maintain an upward draft in all parts of the chamber and to return particles of fuel or foreign substances which may drop to the bottom of the furnace. I have also shown means for forcing air into the furnace chamber at various points in its height, so as to supply the necessary oxygen for complete combustion of the gases evolved from the fuel. The present invention is in the nature of an improvement upon the invention described in said Letters Patent. It is found, in practice, that the coarser particles of material blown upwardly into the furnace through the central nozzle, owing to their inertia, rise higher than the finer fuel and are apt to be blown out of the chamber. To remedy this, I provide in each fuel injecting nozzle a spiral baffle which gives the fuel a swirling motion as it leaves the nozzle, and by this arrangement the heavier particles are thrown by centrifugal force toward the wall of the furnace, instead of being projected in a vertical line, while the finer fuel does not travel directly to the wall but takes initially a more central position in the furnace chamber. The coarser particles are thus prevented from being projected too high in the furnace, and all of the fuel injected is held in suspension.

In the present invention, I have shown the furnace in several connected sections, each section being provided with a fuel injecting nozzle and the spiral deflectors in the adjacent nozzles being reversely arranged, and I have also shown means for admitting air laterally into the several sections at different points in the height of the furnace, the air inlets being located and directed so as to cause a swirl of the fuel and gases in the same direction as the swirl caused by the respective spiral deflectors in the nozzles. In this way, the air, gases and fuel are intermingled without having the currents in one part of the furnace opposed by currents in an adjacent part.

In the accompanying drawing,

Fig. 1 is a horizontal section through the furnace;

Fig. 2 is a section on the line 2—2 of Fig. 1;

Fig. 3 is a section on the line 3—3 of Fig. 1; and,

Fig. 4 is an enlarged sectional view through one of the nozzles and adjacent parts of the furnace.

Referring to the drawing, *a* represents the outer wall of the furnace which, as shown, flares outwardly and upwardly from the bottom, and *b* indicates the combustion chamber enclosed by said wall. The lower part of the combustion chamber is divided into a plurality of compartments 1, 2, 3, and 4 by partitions 5, 6, and 7. Each compartment has a wall formed in cross section on arcs of circles and upwardly flaring, and the chamber wall above the partitions is fluted in continuation of the arcuate walls of the several compartments. Thus, the conical compartments merge into one another above the partitions, and the inner wall of the upper part of the furnace chamber has the arcuate surfaces 1^a, 2^a, etc., concentric with the axes of the fuel injecting nozzles *c*, *c'*, etc.

The fuel injecting nozzles are the same as in my patent referred to above, except that within the bore of the nozzle is arranged a spiral baffle 8, as shown in Fig. 4. The fine fuel is fed to the various nozzles by screw conveyers contained in pipes 9 and is blown upwardly through the nozzle by air admitted from a pipe 10, or a pipe 11. The spiral baffle causes the fuel and air to enter the furnace chamber with a swirling motion and the coarser particles of fuel instead of being projected straight upwardly in the chamber, where they would pass beyond the finer fuel, are thrown outwardly toward the wall and are held in suspension by the upward draft from the nozzle and from the orifice 12, surrounding the nozzle through which air is forced from the pipe 10 or pipe 11.

The spiral baffles in the nozzles in the successive compartments are reversely inclined and the air as well as the fuel injected through the successive nozzles is given a swirling motion in opposite directions, as indicated by the small arrows in Fig. 1. As in the structure of my prior patent, I provide means for admitting air to the combustion chamber, through pipes *d*, at various points in the height of the furnace, for the purpose of supplying the necessary oxygen

to support combustion, and the air inlet openings 13 and 14 above each compartment are at one side of the axis of the compartment, so as to give the air a swirling motion in the same direction as the swirling motion given to the air and fuel by the nozzle of that compartment. Thus, as shown by the larger arrows in Fig. 1, the air, gases and fuel in the successive parts of the furnace are given swirling motions in opposite directions so that the swirl in one part will not counteract that of an adjacent part. This swirling motion causes an intimate mixture of the air and gases and the fresh and ignited fuel.

15 The fuel is ignited initially by the use of suitable oil burners 15, projecting into each compartment, as described in my prior patent, and the heat and gases from the furnace chamber are carried off through a downwardly turned flue 16, as described in my co-pending application Serial Number 25,758, filed April 25, 1925.

It is believed that the operation of the furnace will be clear from the foregoing without further description.

What I claim is:

1. In a furnace for burning fine fuel in suspension, an upwardly flaring combustion chamber, an upwardly directed fuel nozzle at the lower end of said chamber, a spiral deflector in the nozzle, and means for blowing air and fuel into the chamber through the nozzle.

2. In a furnace for burning fine fuel in suspension, an upwardly flaring combustion chamber, an upwardly directed fuel nozzle at the lower end of said chamber, a spiral deflector in the nozzle, an annular air inlet surrounding the nozzle, means for blowing air and fuel into the chamber through the nozzle, and means for blowing air through said air inlet into the chamber.

3. In a furnace for burning fine fuel in suspension, a furnace chamber comprising an upwardly flaring wall, partitions dividing the lower part of the chamber into upwardly flaring compartments, upwardly directed fuel nozzles at the lower ends of the several compartments, a spiral deflector in each nozzle, and means for blowing fuel into the chamber through said nozzles.

4. In a furnace for burning fine fuel in suspension, a furnace chamber comprising an upwardly flaring wall, partitions dividing the lower part of the chamber into upwardly flaring compartments, upwardly directed fuel nozzles at the lower ends of the several compartments, a spiral deflector in each nozzle, the spirals in the successive nozzles being oppositely inclined, and means for blowing fuel into the chamber through said nozzles.

5. In a furnace for burning fine fuel in suspension, a furnace chamber comprising an outer wall and partitions dividing the

lower part of the chamber into compartments, said compartments having walls formed in cross-section on arcs of circles and upwardly flaring and the chamber wall above the partitions being fluted in continuation of the arcuate walls of the several compartments and upwardly flaring, fuel nozzles upwardly directed at the lower ends of the several compartments, and means for blowing air and fuel into said chamber through the nozzles.

6. In a furnace for burning fine fuel in suspension, a furnace chamber comprising an outer wall and partitions dividing the lower part of the chamber into compartments, said compartments having walls formed in cross-section on arcs of circles and upwardly flaring and the chamber wall above the partitions being fluted in continuation of the arcuate walls of the several compartments and upwardly flaring, fuel nozzles upwardly directed at the lower ends of the several compartments, a spiral deflector in each nozzle, and means for blowing air and fuel into said chamber through the nozzles.

7. In a furnace for burning fine fuel in suspension, a furnace chamber comprising an outer wall and partitions dividing the lower part of the chamber into compartments, said compartments having walls formed in cross-section on arcs of circles and upwardly flaring and the chamber wall above the partitions being fluted in continuation of the arcuate walls of the several compartments and upwardly flaring, fuel nozzles upwardly directed at the lower ends of the several compartments, a spiral deflector in each nozzle, the spirals in the successive nozzles being oppositely inclined, and means for blowing air and fuel into said chamber through the nozzles.

8. In a furnace for burning fine fuel in suspension, a furnace chamber comprising an outer wall and partitions dividing the lower part of the chamber into compartments, said compartments having walls formed in cross-section on arcs of circles and outwardly flaring and the chamber wall above the partitions being fluted in continuation of the arcuate walls of the several compartments and upwardly flaring, means for blowing air and fuel into said compartments in such manner as to cause the air and fuel in adjacent compartments to circulate in opposite directions, and means for admitting air laterally into the chamber at various points above the several nozzles and in directions to cause the air, fuel and gases in the upper fluted parts of the chamber to circulate in the same directions as the air and fuel in the compartments.

In testimony whereof I hereunto affix my signature.

JAMES POLLOCK.
